50540	50541	50542	50543	50544	50545	50546	50547	50548	50549	50550	50551	50552	50553	50554	50555	50556	50557	50558	50559	50560	50561	50562	50563	50564	50565	50566	50567	50568	50569	50570	50571	50572	50573	50574	50575	50576	50577	50578	50579	50580	50581	50582	50583	50584	50585	50586	50587	50588	50589	50590	50591	50592	50593	50594	50595	50596	50597	50598	50599	50600	50601	50602	50603	50604	50605	50606	50607	50608	50609	50610	50611	50612	50613	50614	50615	50616	50617	50618	50619	50620	50621	50622	50623	50624	50625	50626	50627	50628	50629	50630	50631	50632	50633	50634	50635	50636	50637	50638	50639	50640	50641	50642	50643	50644	50645	50646	50647	50648	50649	50650	50651	50652	50653	50654	50655	50656	50657	50658	50659	50660	50661	50662	50663	50664	50665	50666	50667	50668	50669	50670	50671	50672	50673	50674	50675	50676	50677	50678	50679	50680	50681	50682	50683	50684	50685	50686	50687	50688	50689	50690	50691	50692	50693	50694	50695	50696	50697	50698	50699	50700	50701	50702	50703	50704	50705	50706	50707	50708	50709	50710	50711	50712	50713	50714	50

1**2,970,758****DEVICE FOR CALCULATING FIRE DEPARTMENT HYDRAULICS**

Frank Anthony Abbate, Pleasantville, N.Y.
(407 Louis Ave., South Floral Park, N.Y.)

Filed May 3, 1956, Ser. No. 582,601

1 Claim. (Cl. 235—87)

This invention relates to computing devices and, more particularly, to apparatus for obtaining accurate hydraulic calculations.

Whenever hydraulic calculations are left to the "rule of thumb" method which is not uniform or standardized, there is a great variation in results depending upon the judgment of the particular individual. An object of this invention, therefore, is to provide accurate computing apparatus for calculating hydraulic data for various diameters of hose and nozzle pressures, which is efficient in operation, simplified in construction, and which will eliminate the aforementioned difficulties.

Another object of this invention is to provide calculating apparatus for determining pump pressure, hose resistance, and maximum effective vertical and horizontal reach, with respect to various nozzle pressures and hose diameters, to provide a uniform and fool-proof procedure for calculating this information.

All of the foregoing and still further objects and advantages of this invention will become apparent from a study of the following specification, taken in connection with the accompanying drawing, wherein:

Figure 1 is a perspective view of a calculating device made in accordance with this invention;

Figure 2 is a view similar to Figure 1, showing one of the major components thereof;

Figure 3 is a view similar to Figure 1, showing another of the major components thereof with parts broken away;

Figure 4 is a lay-out view of the data contained on the component shown in Figure 2; and

Figure 5 is a lay-out view showing the arrangement of various portions contained by the component shown in Figure 3.

Referring now to Figures 1 to 3 of the drawing, a calculating device made in accordance with this invention is shown to include a cylindrical drum 10 having a base 11 at one end and a reduced shaft portion 12 extending throughout the greater portion thereof. A cylindrical sleeve 15 of the same length as the reduced shaft portion 12, is adapted to be carried thereon and abut against the base 11 so as to form a cylinder of constant diameter.

As more clearly shown in Figure 5, the cylindrical sleeve 15 includes a series of spaced window openings 17, 18, 19, 20, and 21 that are arranged around the circumference thereof in a specific pattern. The scale 22 at the inner extremity of the sleeve provides an index for predetermined nozzle pressures between 30 and 70 pounds which pressures are adapted to be in alignment with the respective window openings spaced around the circumference of the sleeve. As shown in Figure 4, the inner

2

edge of the base 11 of the cylindrical drum is provided with a scale 23 having numerically designated indexes in one-eighth intervals between 1 and 1½ to designate nozzle sizes thereby. The entire cylindrical shaft 12 is provided with series of numbers that are arranged in fours so as to be brought into view in the respective window openings of the sleeve. Each group of numbers contained thereon are adapted to provide information of various types. As viewed in Figure 4, the upper left number 10 relates to gallons of flow per minute, the upper right number relates to the resistance of the hose against the flow of water per hundred feet of hose, the lower left number relates to the vertical reach of the stream, and the lower right number relates to the horizontal reach 15 of the stream.

In operation, the assembled device as shown in Figure 1 is set so that the known nozzle pressure on the scale 22 of the sleeve is aligned with the known nozzle size on the scale 23 of the base 11. This is done merely by 20 rotating the sleeve until the desired numbers are opposite each other. In Figure 1, a setting is shown for a nozzle pressure of thirty pounds in a hose of one inch diameter, whereupon by reading the figures in the window opening 17 associated with the thirty pound nozzle pressure scale, 25 the desired data may be obtained; namely, that there will be 164 gallons of flow per minute, 8.04 pounds per square inch of resistance for every hundred feet of hose, the stream will have a vertical reach of 51 feet, and a horizontal reach of 47 feet. It will, therefore, be appreciated, 30 that by setting the device for any combination of known nozzle pressures and hose sizes, the desired data may be readily obtained.

The construction of this device is such that it is compact, efficient in operation, and simple in construction. 35 It is to be noted that the window openings are formed in predetermined spaced relationship circumferentially on the sleeve 15 and that the sleeve cooperates with the base 11 to form a smooth continuous surface that terminates at one end by the base 11 and the other end by the flush 40 association of the shaft 12 with the terminal portion of the sleeve 15.

While this invention has been described with particular reference to the specific form shown in the drawing, it is to be understood that such is not to be construed as imparting limitations upon the invention, which is best defined by the claim appended hereto.

Having thus described my invention, I claim as new and desire to secure by Letters Patent:

A device for calculating fire department hydraulics, including the combination of an elongated cylindrical drum terminating at one end in a cylindrical base portion and having a shaft portion axially aligned with the base portion and of lesser diameter than that of the latter, a cylindrical sleeve rotatably mounted upon the shaft portion 50 and coextensive therewith and at one end abutting the base of said drum and being of substantially equal external diameter as that of the drum so as to present a single continuous cylindrical surface therewith, the base having a first index scale thereon while the mutually 55 abutting portions of the sleeve together forming a second index scale and the shaft having a plurality of predetermined data groups thereon in predetermined arrangement, said sleeve defining a plurality of longitudinally and 60

circumferentially spaced open windows for exposing selected ones of said data groups in response to each setting of the second index scale relative to the first index scale, the windows of the sleeve being corelated with said second index scale while said data groups on said shaft are corelated with said first index scale, said windows and data groups all being disposed in longitudinally spaced relationship respectively along said sleeve and said shaft and readable in the direction parallel to the longitudinal axis of the shaft, the end of said shaft remote from said cylindrical base portion terminating in a plane coinciding with that of the respectively adjacent end of the sleeve in

order to determine the correct assembly of said sleeve with said shaft for accurate operative relationship.
